UNITED STATES PATENT OFFICE

2,488,634

LIFT MECHANISM FOR SLIDING CAR DOORS

Gabriel Madland, Chicago, Ill., assignor to The Youngstown Steel Door Company, Cleveland, Ohio, a corporation of Ohio

Application November 26, 1948, Serial No. 62,064

12 Claims. (Cl. 16—99)

1

This invention relates to lift mechanism for sliding car doors.

It is an object of this invention to provide lift mechanism for sliding doors of railway cars which shall embody means for maintaining the operating lever of said mechanism in vertical position when the doors are in lowered position and prevent whipping of the lever when the cars are in transit.

A further object is to provide mechanism of the character stated above which shall dispense with members heretofore required in similar mechanism while retaining the function of these members.

A further object is to provide mechanism of the character described above which shall obviate punching and consequent distortion and weakening of connecting bars forming a part of such mechanism.

Other objects of the invention will become clear as the description thereof proceeds.

In the drawings forming part of this specification:

Fig. 1 is a fragmentary elevation of a sliding car door equipped with lift mechanism embodying the instant invention, the door being shown in lowered position.

Fig. 2 is a view similar to Fig. 1, the door being shown in elevated position.

Fig. 3 is a section taken on line 3—3 of Fig. 1.

Fig. 4 is a plan view of one of the brackets utilized in the lifting mechanism.

Fig. 5 is an enlarged detail elevation of an assembled bracket and spring actuated plunger of the lift mechanism looking from the back of the bracket.

In the drawings, the lift mechanism embodying the instant invention is shown applied, for the purpose of illustration, to a sliding metallic door 10 for a railway car. As shown, the door embodies a metallic panel 11 formed with spaced horizontal corrugations 12 and reinforced along its front and rear vertical margins by means of members 13 and 14. A metallic plate 15 is secured to the lower margin of the panel 11 as by means of rivets 16. The metallic plate is flanged inwardly as indicated at 17 and then upwardly as shown at 18. The upwardly extending flange 18 is adapted to be secured as by means of welding to the lower edge of the backing plate 19 the upper portion of which is fastened to the metallic panel 11 so as to cooperate therewith and with the plate member 15 to provide a tubular construction within which the lift mechanism is adapted to be disposed.

2

The inwardly extending flange portion 17 of the plate 15 is adapted to engage the horizontal leg 20 of an angular track 21 when the door is lowered so as to frictionally support the door. 5 The track 21 is supported by means of a plurality of brackets 22 which are secured to a member 23 of the car underframe. Disengagement of the door from the track is prevented by means of hook-shaped members 24 secured in any desired manner to the plate member 15 and embracing the depending leg 25 of the track.

The lift mechanism which embodies the instant invention is disposed as indicated above within the tubular formation at the lower edge of the door. This mechanism embodies connecting bars 26 and 27, the adjacent ends of which are provided with elongated openings 28 and 29 into which vertically elongated pinions 30 and 31 extend in order to provide the pivotal connections 10 between an actuating member 32 carrying the pinions and the connecting bars. The actuating member 32 is journaled in the door in any desired manner, reference being made to the patent to Beauchamp, 2,373,447, granted April 10, 1945, 15 for one method of so journaling the actuating member. This member projects outwardly beyond the metallic plate 15 and an operating lever 33 is mounted thereon.

The remote end of connecting bar 26 is secured 20 as by means of rivets 34 to a pair of yoke plates 35 and 36 between which are journalled vertically spaced rollers 37 and 38. Similarly, the remote end of connecting bar 27 is secured as by means 25 of rivets 39 to a pair of yoke plates one of which is shown at 40. A pair of vertically spaced rollers 41 and 42 are journalled between the yoke plates.

A bracket member 43 is secured in any desired 30 manner to the metallic member 15. The bracket member 43 is preferably formed of a short length 35 of angle member so disposed that the horizontal leg 44 thereof is inclined. The horizontal leg 44 is coped in such a manner as to provide an elongated opening 45 and formed so as to provide an upwardly extending inclined tongue 46. 40 The vertical leg 47 of the bracket member is bent so as to provide an inclined flange 48 which overlies the horizontal leg 44. An elongated opening 49 is formed in the flange.

As shown in Fig. 1 of the drawings, the bracket 45 member 43 is disposed so that the horizontal leg 44 is in contact with the roller 38 and the opening 45 therein is so related to the roller that a spring actuated plunger 50 carried by the bracket member will bear against the roller when the door 50 is in lowered position and throughout the eleva-

tion of the door. The plunger 50 which is preferably stamped from a plate embodies an enlarged shouldered lower portion 51 and a narrow shank portion 52 extending upwardly therefrom. A helical spring 53 surrounds the shank portion 52 and bears against the shoulder 54 of the enlarged portion 51 and against the flange 48 of the bracket member. A pin 55 extending through the shank portion 52 above the flange 48 prevents accidental loss of the spring actuated plunger from the bracket.

Again referring to Fig. 1 of the drawings, it will be clear that the spring actuated plunger 50 is inclined to the vertical and is guided in its movement by means of the openings 45 and 49 and the inclined tongue 46. Under the action of the helical spring the pressure of the plunger 50 against the roller 38 urges the operating lever 33 to vertical position and prevents whipping of the lever during the transit of the car upon which the door is mounted.

A bracket member 56 similar in all respects to bracket member 43, except that it is reversed relative thereto and oppositely inclined, is secured to the metallic member 15 in contact with the roller 42. The bracket member 56 carries a spring actuated plunger 57 similar in construction to the spring actuated plunger 50 and oppositely inclined relative thereto. The plunger 57 remains at all times in contact with the roller 42 thereby adding its effort toward maintaining the operating lever 33 in vertical position and preventing whipping of the lever when the car to which the door is applied is in transit.

When the door is in lowered position and frictionally supported upon the track the parts of the lift mechanism are positioned as shown in Fig. 1 of the drawings. Under the action of the spring actuated plungers the operating lever 33 is disposed vertically. In order to elevate the door above the track and support it for movement upon the rollers 37 and 41, the operating lever 33 is swung in the direction of movement of the door. As shown in Fig. 2 of the drawings the door is to be moved along the track toward the right and the operating lever has been swung toward the right. Movement of the operating lever in this direction causes the connecting bars 26 and 27 to approach each other and the rollers 38 and 42 to move along the oppositely inclined brackets 43 and 46 thereby elevating the door above the track 21. As the rollers 38 and 42 move along the brackets, they force the plungers upwardly against the action of the springs and even when fully elevated, these rollers remain in contact with the plungers. The weight of the door has now been transferred to the rollers 37 and 41 and the door may then be moved toward the right upon these rollers.

When it is desired to lower the door, the operating lever 33 is released and the weight of the door upon the rollers 38 and 42 causes them to move away from each other. As the rollers 38 and 42 move oppositely along the brackets 43 and 46, the pressure against the plungers is relieved and they are biased by the action of their springs to maintain contact with the rollers. The operating lever 33 is thereby restored to its vertical position. When the door is lowered the spring actuated plungers through their contact with the rollers 38 and 42 will tend to maintain the operating lever in vertical position and thus avoid whipping of the lever when the car is in transit.

The instant invention embodies the desirable

5 attributes of the invention disclosed in the co-pending application of Thorvald Madland, Serial No. 639,755, filed January 8, 1946, now Patent No. 2,475,507, granted July 5, 1949, while improving upon said invention.

10 It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. In lift mechanism for sliding car doors having a pivotally mounted vertical lever swingable in a plane parallel to the doors, means operatively associated with said lever for movement thereby, and pairs of vertically spaced rollers carried by said means in horizontally spaced relationship, the combination with the upper rollers of said pairs of rollers, of inclined brackets secured to a said door in contact with said upper rollers, inclined guide means on said brackets, plungers disposed in said guide means, and springs engaging said plungers and said brackets and biasing said plungers into engagement with said upper rollers.

2. In lift mechanism for sliding car doors having a pivotally mounted vertical lever swingable in a plane parallel to the doors, means operatively associated with said lever for movement thereby, and pairs of vertically spaced rollers carried by said means in horizontally spaced relationship, the combination with the upper rollers of said pairs of rollers, of inclined brackets secured to a said door in contact with said upper rollers, inclined guide means on said brackets, plungers disposed in said guide means, and springs engaging said plungers and said brackets and biasing said plungers into engagement with said upper rollers.

3. In lift mechanism for sliding car doors having a pivotally mounted vertical lever swingable in a plane parallel to the doors, means operatively associated with said lever for movement thereby, and pairs of vertically spaced rollers carried by said means in horizontally spaced relationship, the combination with the upper rollers of said pairs of rollers, of inclined brackets secured to a said door in contact with said upper rollers, inclined guide means on said brackets, plungers disposed in said guide means, and springs engaging said plungers and said brackets and biasing said plungers into engagement with said upper rollers.

4. In lift mechanism for sliding car doors having a pivotally mounted vertical lever swingable in a plane parallel to the doors, means operatively associated with said lever for movement thereby, and pairs of vertically spaced rollers carried by said means in horizontally spaced relationship, the combination with the upper rollers of said pairs of rollers, of inclined brackets secured to a said door in contact with said upper rollers, inclined guide means on said brackets, plungers disposed in said guide means, and springs engaging said plungers and said brackets and biasing said plungers into engagement with said upper rollers.

5. In lift mechanism for sliding car doors having a pivotally mounted vertical lever swingable in a plane parallel to the doors, means operatively associated with said lever for movement thereby, and pairs of vertically spaced rollers carried by said means in horizontally spaced relationship, the combination with the upper rollers of said pairs of rollers, of inclined brackets secured to a said door in contact with said upper rollers, inclined guide means on said brackets, plungers disposed in said guide means, and springs engaging said plungers and said brackets and biasing said plungers into engagement with said upper rollers.

6. In lift mechanism for sliding car doors having a pivotally mounted vertical lever swingable in a plane parallel to the doors, means operatively associated with said lever for movement thereby, and pairs of vertically spaced rollers carried by said means in horizontally spaced relationship, the combination with the upper rollers of said pairs of rollers, of inclined brackets secured to a said door in contact with said upper rollers, inclined guide means on said brackets, plungers disposed in said guide means, and springs engaging said plungers and said brackets and biasing said plungers into engagement with said upper rollers.

7. In lift mechanism for sliding car doors having a pivotally mounted vertical lever swingable in a plane parallel to the doors, means operatively associated with said lever for movement thereby, and pairs of vertically spaced rollers carried by said means in horizontally spaced relationship, the combination with the upper rollers of said pairs of rollers, of inclined brackets secured to a said door in contact with said upper rollers, inclined guide means on said brackets, plungers disposed in said guide means, and springs engaging said plungers and said brackets and biasing said plungers into engagement with said upper rollers.

8. In lift mechanism for sliding car doors having a pivotally mounted vertical lever swingable in a plane parallel to the doors, means operatively associated with said lever for movement thereby, and pairs of vertically spaced rollers carried by said means in horizontally spaced relationship, the combination with the upper rollers of said pairs of rollers, of inclined brackets secured to a said door in contact with said upper rollers, inclined guide means on said brackets, plungers disposed in said guide means, and springs engaging said plungers and said brackets and biasing said plungers into engagement with said upper rollers, said plungers remaining in engagement with said upper rollers throughout the lifting movement of said doors.

9. In lift mechanism for sliding car doors having a pivotally mounted vertical lever swingable in a plane parallel to the doors, means operatively associated with said lever for movement thereby, and pairs of vertically spaced rollers carried by said means in horizontally spaced relationship, the combination with the upper rollers of said pairs of rollers, of inclined brackets secured to a said door in contact with said upper rollers, vertically spaced overlapping flanges on said brackets, offset openings formed in said flanges providing inclined guides, plungers extending through said openings, and springs engaging the upper of said overlapping flanges and said plungers and biasing the latter into engagement with said upper rollers.

10. In lift mechanism for sliding car doors having a pivotally mounted vertical lever swingable

in a plane parallel to the doors, means operatively associated with said lever for movement thereby, and pairs of vertically spaced rollers carried by said means in horizontally spaced relationship, the combination with the upper rollers of said pairs of rollers of inclined brackets secured to a said door in contact with said upper rollers, vertically spaced overlapping flanges on said brackets, offset openings formed in said flanges, tongues struck upwardly from the lower of said overlapping flanges adjacent to the opening therein, plungers extending through said openings in proximate relationship to said tongues, and springs engaging the upper of said overlapping flanges and said plungers and biasing the latter into engagement with said upper rollers.

6. In lift mechanism for sliding car doors having a pivotally mounted vertical lever swingable in a plane parallel to the doors, means operatively associated with said lever for movement thereby, and pairs of vertically spaced rollers carried by said means in horizontally spaced relationship, the combination with the upper rollers of said pairs of rollers, of inclined brackets secured to a said door in contact with said upper rollers, vertically spaced overlapping flanges on said brackets, offset openings formed in said flanges providing inclined guides, plungers extending through said openings, shoulders formed on said plungers, springs engaging the upper of said overlapping flanges and said shoulders and biasing said plungers into engagement with said upper rollers, and means carried by said plungers and engageable with said upper flanges to prevent disengagement of said plungers from said brackets.

7. In lift mechanism for sliding car doors having a pivotally mounted vertical lever swingable in a plane parallel to the doors, means operatively associated with said lever for movement thereby, and vertically spaced rollers carried by said means, the combination with the upper of said rollers of an inclined bracket secured to a said door in contact with said upper roller, inclined guide means on said bracket, a plunger disposed in said guide means, and a spring engaging said plunger and said bracket and biasing said plunger into engagement with said upper roller.

8. As an article of manufacture a combined bracket and spring pressed plunger for use in lift mechanism for sliding car doors comprising a bracket, guide means on said bracket, a plunger disposed in said guide means, a spring engaging said plunger and said bracket and biasing said plunger in one direction, and means carried by said plunger and engageable with said bracket for limiting movement of said plunger in said one direction.

9. As an article of manufacture a combined bracket and spring pressed plunger for use in lift mechanism for sliding car doors comprising

a bracket, a vertically spaced overlapping flanges on said bracket, offset openings formed in said flanges providing guides, a plunger extending through said openings, a spring engaging the upper of said overlapping flanges and said plungers and biasing the latter in one direction, and means carried by said plunger and engageable with said upper flange for limiting movement of said plunger in said one direction.

10. In lift mechanism for sliding car doors having pivotally mounted lever means swingable in either direction in a plane parallel to the doors, connecting bars the adjacent ends of which are pivotally connected to said lever means, and pairs of vertically spaced rollers carried by the remote ends of said bars, the combination with the upper rollers of said pairs of rollers of inclined brackets secured to said doors in contact with said upper rollers, inclined guide means on said brackets, plungers disposed in said guide means and springs engaging said plungers and said brackets and biasing said plungers into engagement with said upper rollers.

11. In lift mechanism for sliding car doors having a pivotally mounted vertical lever swingable in a plane parallel to the doors, means operatively associated with said lever for movement thereby, and pairs of vertically spaced rollers carried by said means in horizontally spaced relationship, the combination with the upper rollers of said pairs of rollers, of inclined brackets secured to a said door in contact with said upper rollers, guide means on said brackets, plungers disposed in said guide means, and springs engaging said plungers and said brackets and biasing said plungers into engagement with said upper rollers.

12. In lift mechanism for sliding car doors having a pivotally mounted vertical lever swingable in a plane parallel to the doors, means operatively associated with said lever for movement thereby, and pairs of vertically spaced rollers carried by said means in horizontally spaced relationship, the combination with the upper rollers of said pairs of rollers, of oppositely inclined brackets secured to a said door in contact with said upper rollers, guide means on said brackets, plungers disposed in said guide means, and springs engaging said plungers and said brackets and biasing said plungers into engagement with said upper rollers.
